ELECTRIC MOTOR

Robert Page Burr and Raymond J. Keogh, Huntington,
N.Y., assignors to Photocircuits Division of Kollmorgen
Corporation, Glen Cove, N.Y.

Filed Jan. 11, 1972, Ser. No. 217,081

Term of patent 14 years

Int. Cl. D13—01

U.S. Cl. D26—5 A

FIG. 1

FIG. 2

FIG. 4

FIG. 3

FIG. 1 is a perspective view of an electric motor embodying our new design showing the top, one side and one end thereof;

FIG. 2 is a perspective view of the electric motor of FIG. 1; showing the bottom, opposite side and opposite end thereof.

FIG. 3 is a top plan view of the electric motor of FIG. 1 showing the opposite side thereof; and

FIG. 4 is an end elevational view of the new design showing the right end thereof.

We claim:

The ornamental design for an electric motor, as shown.
